UNITED STATES PATENT OFFICE.

EARL ACKER, OF INDIANAPOLIS, INDIANA.

COMBINED WINDOW-SHADE SUPPORT AND CURTAIN-HANGER.

1,181, /14.

Specification of Letters Patent.

Patented May 2, 1916.

Application filed November 23, 1914. Serial No. 873,552.

To all whom it may concern:

Be it known that I, EARL ACKER, residing at Indianapolis, in the county of Marion and State of Indiana, have invented certain new and useful Improvements in Combined Window-Shade Supports and Curtain-Hangers; and I do hereby declare the following to be a full, clear, and exact description of the invention, such as will enable others skilled 10 in the art to which it appertains to make and use the same.

This invention relates to combined window shade supports and curtain hangers, and one of the principal objects of the invention is to provide a device for supporting the rollers of window shades and at the same time supporting the lace curtain pole, and to provide means whereby the entire device may be connected to a window frame 20 without the use of nails or tools.

Another object of the invention is to provide a shade support and curtain hanger for double windows, or windows side by side, in which a single device is secured centrally 25 and at the top of both windows to support two shades and two curtain poles or curtain.

The foregoing and other objects may be attained by means of the construction illustrated in the accompanying drawings, in 30 which,

Figure 1 is a front elevation of a combined window shade support and curtain hanger applied to two windows side by side and made in accordance with this invention, 35 Fig. 2 is a sectional view taken through the central and double bracket member made on a larger scale, Fig. 3 is a side elevation of one of the brackets and its support, Fig. 4 is a front elevation of a single combined 40 shade support and curtain pole hanger applied to a single window frame, and Fig. 5 is a perspective view of one of the end brackets.

Referring to Fig. 1 of the drawing, the 45 numeral 1 designates the window frame of a double window having a central dividing panel 2, and supported upon the window casing in the top thereof is a double bracket, comprising a base plate 3 having its ends 4 50 bent at right angles and provided with prongs 5 to engage the window casing. Mounted on the base plate 3 is a curtain pole bracket 6, the outer end of which is provided with a curved recess 7 and an up- 55 wardly extending hook 8. Connected to the outer end of the angular portion 9 of the

curtain pole bracket 6 are spiral springs 10, and connected to the opposite end of the base plate 3 are spiral springs 11. The springs 10 and 11 are each connected to the 60 end brackets of the shade support and curtain hanger. Mounted upon the base plate 3 at opposite sides of the window curtain bracket 6 are shade brackets 12 and 13, said brackets having angular portions provided 65 with bent over ears or flanges 14 and 15 which engage the base member 3 and slide thereon to compensate for shade rollers of the different lengths, one of said brackets having a squared hole 16 while the other is 70 provided with a round hole for the spindles of the shade rollers.

The end brackets each comprise the base plate 17, each provided with downturned feet 18 also having prongs to engage the 7 outer sides of the window frame, and the springs 10 and 11 are connected to these base plates to insure the engagement of the prongs on the feet 18 with the outer sides of the 8 window casing. Mounted on each of the 8 base plates 17 is an adjustable shade bracket 19 formed from a single piece of sheet metal and having an outwardly bent bracket member 20, while the strip which engages the base 17 is bent over the top and bottom 8 thereof to slide thereon to accommodate rollers of different lengths. Formed integral with the base plates 17 are curtain pole brackets 21 which extend outward at right angles to the base plate, as shown.

Referring to Figs. 4 and 5 of the drawings, in which a single form of window shade support and hanger is shown, the base plates 17 are identical with those illustrated in Fig. 1 of the drawing and are connected together by means of the spiral springs 10, said springs being connected at their ends to perforations 22.

From the foregoing it will be obvious that the combined window shade support and curtain hanger can be placed upon a window without the necessity of tools or fastening devices, since the springs will draw the devices one toward the other and hold them firmly in connection with the window casing. It will also be obvious that the bracket for the window shade may be adjusted toward and from one another to compensate for different lengths of rollers and one of said brackets being provided with a round hole and the other a square one for the rollers.

Various changes may be made in the de-

tails of construction without departing from the spirit and scope of the invention as defined in the claim.

What is claimed is:—

- 5 The combination with a shade bracket and curtain hanger comprising a base plate having one of its ends bifurcated and bent at right angles forming arms, said arms provided on their inner faces with tongues for 10 engaging a window casing, an arm formed on one face of said base plate at the point of juncture of said arm with said base plate, said arm extending outwardly therefrom, its outer end provided with a cutaway portion adapted to receive a curtain pole there- 15

in, a shade bracket including a body having its opposite ends turned in forming flanges to slidably engage the opposite side longitudinal edges of the first named plate, and a shade supporting arm formed on one of the 20 vertical edges of said body intermediate its ends and supporting a shade roller therein, substantially as set forth.

In testimony whereof I affix my signature in presence of two witnesses.

EARL ACKER.
